(57) **CLAIM**

The ornamental design for a casting machine, as shown and described.

DESCRIPTION

FIG. 1 is a front view of a casting machine of the present invention, including surrounding wall portions, a main body portion, a lower mold portion, and an upper mold portion.

FIG. 2 is a rear view of the casting machine of FIG. 1.

FIG. 3 is a top plan view of the casting machine of FIG. 1.

FIG. 4 is a bottom plan view of the casting machine of FIG. 1.

FIG. 5 is a right side view of the casting machine of FIG. 1.

FIG. 6 is a left side view of the casting machine of FIG. 1.

FIG. 7 is a perspective view of the casting machine of FIG. 1.

FIG. 8 is a perspective view of the main body portion of the casting machine & FIG. 1, which is equivalent to the perspective view of the casting machine of the FIG. 1 without the surrounding wall portions shown removed for clarity of disclosure.

FIG. 9 is a perspective view of the main body portion of the casting machine of FIG. 1, which is equivalent to the perspective view of the casting machine of FIG. 1 without the surrounding wall portions, showing the lower mold portion moved forward and shown removed for clarity of disclosure.

FIG. 10 is a perspective view of the main body portion of the casting machine of FIG. 1, which is equivalent to the perspective view of the casting machine of FIG. 1 without the surrounding wall portions, showing the upper and lower mold portions in a closed state and shown removed for clarity of disclosure.

FIG. 11 is a perspective view of the main body portion of the casting machine of FIG. 1, which is equivalent to the perspective view of the casting machine of the FIG. 1 without the surrounding wall portions, showing the mold portions in a tilted state; and,

FIG. 12 is a perspective view of the main body portion of the casting machine of FIG. 1, which is equivalent to the perspective view of the casting machine of the FIG. 1 without the surrounding wall portions, showing the upper mold portion moved forward.
